Edward T. Johnson, Los Angeles, Calif.

Application October 20, 1945, Serial No. 123,041

Term of patent 14 years

(Cl. D33—19)

To all whom it may concern:

Be it known that I, Edward T. Johnson, a citizen of the United States of America and a resident of the city of Los Angeles, in the county of Los Angeles and State of California, have invented a new, original, and ornamental Design for a Portable Bar, of which the following is a specification, reference being had to the accompanying drawing, forming part thereof.

In the drawing:

I claim:

The ornamental design for a portable bar, substantially as shown.

EDWARD T. JOHNSON.
